DESIGN FOR A SHANK FOR A FINGER RING

Earl Kiff, Attleboro, Mass., assignor to L. G.
Balfour Company, a corporation of Massachusetts

Application November 1, 1944, Serial No. 116,089

Term of patent 7 years

(Cl. D45—10)

To all whom it may concern:

Be it known that I, Earl Kiff, a citizen of the United States, residing in Attleboro, county of Bristol, and State of Massachusetts, have invented a new, original, and ornamental Design for a Shank for a Finger Ring, of which the following is a specification, reference being had to the accompanying drawing, forming a part thereof.

I claim:

The ornamental design for a shank for a finger ring, substantially as shown.

EARL KIFF.
